RUFUS R. MCKNIGHT AND ARTHUR WEBBER, OF CHICAGO, ILLINOIS, ASSIGNEES TO
THE DE MOE ENGINEERING LABORATORIES, INC., OF CHICAGO, ILLINOIS, A CORPO-
RATION OF ILLINOIS

AUTOMOTIVE STEAM GENERATOR

Application filed February 5, 1930. Serial No. 425,975.

This invention relates to improvements in automotive steam generators.

This invention has reference to automotive steam generators of the type particularly set forth and described in co-pending application, Serial No. 187,377, patented March 31, 1931 Patent No. 1,798,550 and the object of the present invention is to improve the construction of a steam generator of this character in such a way as to prevent a siphoning out of the water from the boiler tubes by the sudden evolution of steam.

As shown, the special features of the present invention are combined in a steam generator which possesses the features of compactness, flexibility, efficiency, and rapidity of steam generation in a type of power unit adapted for use in the driving of vehicles, although the special features of the present invention are not in any way limited to a generator of this specific character.

In the present embodiment of the invention, the generator as a whole includes groups of preheating drums arranged below the fire level, together with groups of drums above the fire level, and connected with the lower drums by tubes which surround the heating zone.

The steam evolved in the upper groups of drums traverses a circuitous pathway from drum to drum and is ultimately delivered to a super-heating drum immediately above the fire zone, from which the super-heated steam is delivered to the throttle.

In the passage of the steam through the upper groups of drums, difficulty has been experienced in the maintenance of a proper water level, and in the return flow of condensation, by reason of the tendency of the steam, at the point of its evolution, to suck out or siphon out the water and thus interfere with the proper operation of the generator. The present invention is intended to overcome this difficulty by the provision of adequate drum connections, arranged in each instance at the proper levels to prevent or destroy this siphoning action, and at the same time to afford adequate communication between the drums of the several groups, so that the steam will pass unrestrictedly to the super-heater

without disturbing the intended water level, at the point where the water is intended to flash into steam.

Other objects and details of the invention will appear from a description thereof, in conjunction with the accompanying drawings, wherein,

Figure 1 is a vertical section, taken longitudinally of the generator;

Fig. 2 is a horizontal sectional view, taken on line 2—2 of Figure 1, showing the preheating drums at the bottom of the generator;

Fig. 3 is a front elevation of the generator with the housing removed; and

Fig. 4 is a rear elevation of the generator with the housing removed.

In the present exemplification of the invention, the generator comprises an insulated housing 10 of rectangular or boxlike formation, which encloses all of the drums and tubes comprising the generator as a whole.

The preheating drums arranged at the bottom of the housing comprise a pair of centrally disposed drums 11 which are connected at their inner ends by a high level cross tube 12, together with two pairs of outer drums 13—14, each pair being connected, at the forward ends of the drums, by a high level cross connecting tube 15.

Water is admitted to one of the inner drums 11 through an inlet tube 16, and all of the remaining drums are cross connected at their rear ends by a low level cross header tube 17. The two inner drums 11 are of less length than the groups of outer drums, which arrangement affords space for the location of a burner 18.

The tubes are arranged in the form of transversely extending banks which are connected at their lower ends to the outermost preheating drums 14. Each bank includes a lower cross header 19 and an upper cross header 20, and between the headers are arranged groups of tubes 21. The lower headers slope obliquely upward from short pipe sections 22, which furnish the connections with the outer preheating drums, and the arrangement is one in which the tube banks stand in interspersed relation to one another;

that is to say, the lower tube headers are alternately connected with the respective outermost preheating drums and alternately slope upward from opposite sides, so that throughout the entire series the alternate banks of tubes will be connected with one of the outermost preheating drums, and the intervening banks of tubes will be connected with the other.

- 10 In order to provide an unimpeded heat zone in proximity to the burner 18, the banks of tubes in the series from rear to front stand in progressively increasing forward obliquity to the vertical, or in fan-shaped arrangement 15 as viewed in Fig. 1, which affords an upwardly tapering fire space near the front side of the generator.

In order to increase the heating surface, two longitudinally standing banks of tubes 20 23, one on each side of the fire zone, are provided, which banks are connected with headers 24 and 25.

The group arrangement of the headers and tubes heretofore described is that set forth 25 in co-pending application Serial No. 187,877, and serves to indicate the general arrangement of a generator conformable to the principles of the present invention, but the special features now to be described are included in 30 the upper group of headers located above the fire zone, with which the banks of tubes communicate and which will now be described in detail.

The upper tube headers of the tube banks 35 which are connected with the outermost preheating drum on one side of the generator, connect with a distributing drum 26 through pipe sections 27 on the opposite side of the generator, so that in each instance there will 40 be a cross flow of water transversely of the generator, in conformity with the interspersed arrangement of the banks of tubes.

The distributing drums 26 are located respectively on opposite sides of the medial 45 plane of the generator, and a description of the drum arrangement on one side will suffice for both.

Each of the distributing drums 26 underlies a pair of drums 28, which drums collectively across the generator form a higher tier 50 of drums, and the intended water level lies at or near the upper level of this tier of four drums 28, at which point the water flashes into steam.

Each of the distributing drums 26 is connected with the superposed pair of water level drums 28, at recurrent intervals, by the provision of diagonally extending tube 60 connections 29, and in turn each pair of drums 28 is similarly connected with an elevated intermediate drum 30 through the provision of tube sections 31.

Immediately on each side of each of the 65 intermediate drums 30 is located a drum 32,

and each drum 30 with the associated drums 32 is connected at the front end by a low level cross tube 33 and at the rear end by a low level cross tube 34, which tubes serve to unite the drums 30—32 at each end into a group of three drums, of which the intermediate drum 30 stands at a slightly lower level than the associated drums 32.

In addition to the front and rear cross tubes 33 and 34, which may be termed the lower cross tubes, the same group of three drums is additionally connected at the front end by a bowed or curved upper cross tube 35, which enters the drums 32 at a distinct elevation above the center of the drums, and the same drums are connected at the rear end by means of an upper cross tube 36, which enters the drums 32 at substantially the vertical center. This arrangement provides for this group of three drums what may be termed a low level connection comprising the cross tubes 33—34, and a high level connection comprising the cross tubes 35—36. The purpose and function of this arrangement will be presently explained.

Above the group of drums just described is located a similarly arranged group of upper drums, including a center drum 37 and slightly elevated side drums 38, which latter are recurrently connected with the underlying drums 32 by short tube connections 39, which enter the walls of the respective drums along the lines of closest proximity, and the drums 32—38 are additionally connected at the front ends by more elongated tube connections 40, which enter the drums 32 slightly below the top level and enter the drums 38 at a point slightly above the vertical center.

In addition, the group of three upper 105 drums 37—38—38 are connected at their front ends by a cross tube 41, which enters the center drum near the upper level thereof, and enters the side drums 38 at or near the center. Similar tube connections 42—42 are 110 provided at the rear ends for connecting the superposed drums 38—32, and a similar rear cross tube 43 connects the upper group of three drums.

The upper groups of three drums on each 115 side of the medial plane of the generator are respectively connected to a superheater drum 44 by means of a front T-shaped tube connection 45, the horizontal arms of which enter the respective center drums 37 near the 120 lower level thereof, and unite with the vertical arm of the T which leads downwardly to the superheater drum which is centrally located at a point immediately above the fire zone and in the region of highest temperature.

The T-shaped tube connection 45 also serves as a support or hanger for the front end of the superheater drum and is supplemented by a T-shaped bracket 46 at the rear 130

end, which is welded or otherwise secured to the central adjacent drums 32—32 and to the rear end of the superheater drum 44.

The T-shaped tube connection 45 is supplemented by an upper T-shaped extension 47, the arms of which enter the top of the center drums 37 of the upper group, and the T-extension leads downwardly and is centrally entered into the T tube connection 45, so that, in effect, a double cross connection is provided, which affords lower and upper level connections between the drums 37 at or near the front ends only.

The superheater drum has leading therefrom a steam pipe 48 which carries superheated steam to the throttle of the engine with which the generator is associated. The normal water level will be at or near the top of the drums 28, at which point the generation of steam takes place, and the steam will thereupon be discharged into the center drums 30 of the lower group and be thence distributed to the drums 32 of the lower group and from them to the drums of the upper group, and ultimately carried downwardly into the superheater.

The evolution of steam within the drums 28 may tend to create a suction or siphoning action at this point which will have the effect of sucking the water upwardly above the intended water level and thus interfering with the evolution of the steam. It is to overcome this tendency that the three drums of the lower group are doubly connected, both by a high level connection and by a low level connection, and for the same reason the superposed drums of the upper and lower groups are likewise connected at different levels. This establishes diversely elevated lines of connection between the drums, so that the tendency to establish and maintain a suction line will be prevented, and the suction or siphoning effect destroyed, so that the water will be uniformly maintained at the intended level and will not be drawn into the steam line and interfere with the circulation of the steam through the respective groups of drums and its ultimate discharge into the superheater.

Although the high and low level connections are shown as applied to drums arranged in upper and lower groups, the principle involved is adapted for use with groups of drums variously arranged and connected, and it will be thus understood that the group series shown serves simply for purposes of exemplification and that it is not the intention to limit the invention save in the manner indicated in the claims.

It will be understood that by providing upper and lower groups of connections, the return flow of water of condensation will be unimpeded by the upward movement of the steam, so that water will not be trapped and carried forward into the steam line.

Although the invention has been described as one which is particularly adapted for use in a generator intended for automotive use, the principles involved have more general application and may be employed in many cases where single level connections would tend to establish and maintain a suction line with the resultant siphoning effect on the water. 70

We claim:

1. In a steam generator, the combination of 75 heating tubes, means for heating the tubes, a water level drum with which the heating tubes are connected, a plurality of steam drums located above the water level drum and connected therewith, and high level and low level connections between the steam drums and adapted to prevent the siphoning of water, and means for educting steam from the steam drums.

2. In a steam generator, the combination 85 of heating tubes, a water level drum with which the heating tubes are connected, a group of three steam drums located above the water level drum and connected therewith, and high level and low level connections 90 between the steam drums and adapted to prevent the siphoning of water through the steam drums, and means for educting steam from the steam drums.

3. In a steam generator, the combination 95 of heating tubes, a water level drum with which the heating tubes are connected, a group of three steam drums located above the water level drum and connected therewith, and high level and low level connections 100 between the ends of the steam drums and adapted to prevent the siphoning of water through the steam drums, and means for educting steam from the steam drums.

4. In a steam generator, the combination 105 of heating tubes, a distributor drum located above and connected with the heating tubes, a pair of water level drums connected with the distributor drum, a group of three steam drums located above the water level drums, 110 the center drum of said group being connected with the water level drums, high level and low level connections between the group of three steam drums and adapted to prevent the siphoning of water through the drums, 115 and means for educting steam from the steam drums.

5. In a steam generator, the combination 120 of heating tubes, a distributor drum located above and connected with the heating tubes, a pair of water level drums connected with the distributor drum, a lower group of three steam drums located above the water level drums, the center drum of said lower group being connected with the water level drums, 125 high level and low level connections between the three drums of the lower group and adapted to prevent the siphoning of water, an upper group of three steam drums, the outer drums of the upper group being connected with the 130

In witness that we claim the foregoing we have hereunto subscribed our names this 24th day of January, 1930.

RUFUS R. McKNIGHT.
ARTHUR WEBBER.

70

outer drums of the lower group by two sets of connections entering the respective drums at different levels, and the three drums of the upper group being inter-connected, and means for educting steam from the upper group of drums.

6. In a steam generator, the combination of heating tubes, a distributor drum located above and connected with the heating tubes, 10 a pair of water level drums connected with the distributor drums, a lower group of three drums located above the water level drums, the center drum of said lower group being connected with the water level drums, high 15 level and low level connections between the three drums of the lower group and adapted to prevent the siphoning of water, an upper group of three steam drums, the outer drums of the upper group being connected with the outer drums of the lower group by two sets 20 of connections entering the respective drums at different levels, and the three drums of the upper group being inter-connected, and means for educting steam from the upper 25 group of drums, said means including connections entering one of the drums of said group at different levels.

7. In a steam generator, the combination of heating tubes, a distributor drum located 25 above and connected with the heating tubes, a pair of water level drums connected with the distributor drum, a lower group of three drums located above the water level drums, the center drum of said lower group being 30 connected with the water level drums, high level and low level connections between the three drums of the lower group and adapted to prevent the siphoning of water, an upper group of three steam drums, the outer drums 35 of the upper group being connected with the outer drums of the lower group by two sets of connections entering the respective drums at different levels, and the three drums of the upper group being inter-connected, and 40 means for educting steam from the upper group of drums, said means including connections entering one of the drums of said group at different levels, and a superheater drum located below the water level drums and 45 with which said steam educting means communicates.

8. In a steam generator, the combination of vertically disposed heating tubes, means for heating the tubes, three horizontally disposed drums grouped together at substantially the same level above the heating tubes, a connection between at least one of the drums of said group and the heating tubes, and a high level and a low level cross connection 55 between the three drums composing the group, adapted to prevent the siphoning of water through the drums, and means for educting steam from the interconnected drums, and a separate heater drum with 60 which said educting means communicate.
